DESIGN FOR A COMBINED MATCH CLUSTER AND HOLDER

Morris A. Bell, Oshkosh, Wis., assignor to The
Bell Machine Company, Oshkosh, Wis.

Application June 27, 1935, Serial No. 57,436

Term of patent 3½ years

To all whom it may concern:

Be it known that I, Morris A. Bell, a citizen of the United States, residing at Oshkosh, in the county of Winnebago and State of Wisconsin, have invented a new, original, and ornamental Design for a Combined Match Cluster and Holder, as shown in the accompanying drawing, and described in the following specification.

In the drawing:

Figure 1 is a side elevational view of the com-

bined match cluster and holder showing my new design;

Figure 2 is a top plan view showing only a portion of the match cluster; and

Figure 3 is an end elevation thereof.

I claim:

The ornamental design for a combined match cluster and holder, as shown and described.

MORRIS A. BELL.
